UNITED STATES PATENT OFFICE.

JOHN B. LOTT, OF ANDERSON, INDIANA.

MEANS FOR MOUNTING RAILS ON CONCRETE FOUNDATIONS.

Application filed July 24, 1920. Serial No. 398,624.

To all whom it may concern:

Be it known that I, JOHN B. LOTT, a citizen of the United States, and resident of Anderson, in the county of Madison and 5 State of Indiana, have invented certain new and useful Improvements in Means for Mounting Rails on Concrete Foundations, of which the following is a specification.

My invention relates to improvements in 10 devices employed for mounting railway rails on longitudinally disposed concrete ties or rail foundations, and it is especially designed as an improvement upon similar devices described in my prior patents dated 15 December 19, 1911, and August 8, 1916, and numbered 1,011,978 and 1,193,573 respectively.

As defined in general terms both of my 20 prior patents contemplate mounting a single cushioning element between the base of a rail and the top of its concrete foundation, and the rail and cushioning element are fastened directly to the foundation by bolts anchored therein. My present invention, 25 however, is not only an improvement upon my former attaching means for the rail, but it is especially designed to provide means for preventing lateral movement of a rail with respect to its foundation or tie, and to 30 provide what may be termed a double cushion between the rail and its foundation or tie.

More specifically, the principal objects of 35 my present invention are; to provide a cushioned base plate having longitudinal guard flanges for preventing lateral movement of a rail mounted therebetween; to provide means for anchoring the base plate in the foundation and positively, but removably securing the same thereto; to provide unitary means for primarily securing a rail in 40 place between the guard flanges of the base plate and secondarily serving as an attaching element for maintaining the base plate securely upon a foundation; and to provide a 45 cushioning element between the rail and the base plate for absorbing in conjunction with the first mentioned cushioning element excessive vibration due to the passage of rolling stock over the rails.

To these and other ends, my invention 50 consists in the construction, arrangement and combination of parts described herein-after and pointed out in the claims.

The preferred embodiments of my invention 55 are represented by way of example in the accompanying drawings, where

Fig. 1 is a sectional view of the preferred embodiment of my invention;

Fig. 2, a top plan view of the embodiment 60 illustrated in Fig. 1;

Fig. 3, a detail perspective of the base plate;

Fig. 4, a sectional view showing a slight modification of the concrete foundation or tie and attaching means for the base plate 65 disposed thereon; and

Fig. 5, a modified form of base plate which is formed with a portion thereof serving as an anchor embedded in the concrete foundation. 70

Like characters of reference designate like or similar parts throughout the several views of the drawings, in which:—

A designates a longitudinal concrete rail foundation or tie similar in construction to 75 that described in my prior Patent No. 1,011,978, and which in the present instance is formed with a longitudinal groove or channel 1 designed for the reception of an anchoring flange 2 formed on the base 3 of 80 the base-plate 4. Between the base-plate 4 and the top of the foundation A is disposed a cushioning member 5 of wood or other suitable material, and upon the upper face of the base plate are formed a pair of complementary, parallel guard flanges 6 having sloping exterior sides 7. Carried between the guard flanges 6 is a second cushioning member 8 upon which is mounted a railway rail B. In the present instance the rail B is 90 formed with suitable openings in its base for receiving securing bolts 9 which pass through the base 3 of the base-plate 4 and the cushioning member 5 into the concrete foundation A where their ends are hooked 95 and embedded to securely hold them in place. It will be noted that the bolts 9 serve to hold all of the foregoing elements in assembly, but to insure against possible loosening or displacement of the base-plate 100 4 other stay bolts 10 are provided which extend into engagement with tie-plates 11 mounted across the bottom of the foundation A.

In order to remove the rails and other elements including the base plates and cushioning members it is merely necessary to remove the nuts from the bolts 9 and 10, but when the road is set up possible loosening or spreading of the rails is positively prevented, 110 and furthermore, the rail cushioning members 8 and the bolts 9 together with the base .

2
of the rails are protected by the guard flanges 6 on the base-plates.

In the slight modification illustrated in Fig. 4, the construction of the cushioning members, base plate, guard flanges, and rail securing bolts is the same as in the preferred embodiment, but the concrete foundation or tie A' is formed with lateral extensions 12. These extensions 12 serve to increase the 10 breadth of the top of the foundation which in the present embodiment is cut away as at 13 to form a seat for the cushioning member 5 and base-plate 4. Furthermore, the bolts 10 in the present instance are mounted in the 15 extensions 12 thus eliminating the use of tie-plates 11 as in the preferred embodiment of the invention.

The embodiment of the invention as illustrated in Fig. 5 contemplates forming the 20 base-plate 4 with an enlarged base 14 which is embedded in the concrete foundation as illustrated, and has formed therein a plurality of openings 15 and ribs 16 in and about which the concrete sets to firmly 25 anchor the base-plate in position. The bolts 9 in this modification are not anchored in the concrete as in the previous embodiments but are screwed directly into the base plate, and the use of a cushioning member between the 30 foundation and base plate (as in Figures 1, 2, 3 and 4) is dispensed with.

The railroad construction contemplated in my present invention is particularly adapted to crossings, where vehicle traffic must be 35 contended with as well as the usual rolling stock, for the usual cross-ties of wood become quickly worn out and the continual jolts delivered on the rails by wheels quickly cause loosening and spreading of the rails. Furthermore where longitudinal concrete 40 foundations are in common use the method of securing the rails thereon is a decided improvement over the securing means heretofore used. Attention is also particularly 45 called to the fact that the securing means for the rails as contemplated in the present invention is applicable to use with the road-bed and foundation construction described in my prior Patents Numbers 1,011,978 and 50 1,193,573.

While in the foregoing, there has been illustrated in the drawings and described in the specification such combination and arrangement of elements as constitute the pre-

fferred embodiments of this invention, it is 55 nevertheless desired to emphasize the fact that interpretation should only be conclusive when made in the light of the subjoined claims.

Having described my invention and its 60 objects with such attention to detail as will thoroughly acquaint one skilled in the art with its construction and advantages I claim:

1. Means for mounting rails on concrete 65 foundations, comprising a base plate, means integral with the base plate on each side of a rail preventing lateral movement of the rail with respect to the plate, and separate means anchored to a concrete foundation and 70 extending through the rail base to secure the rail against vertical upward movement with respect to said base plate.

2. Means for mounting rails on concrete 75 foundations, comprising a base plate, means formed on the base plate for anchoring the same to a concrete foundation, means integral with the base plate on each side of a rail preventing lateral movement of the rail with respect to the plate and separate means 80 extending through the rail base for holding the rail against upward movement with respect to the base plate.

3. Means for mounting rails on concrete 85 foundations comprising a base plate, means formed on the base plate for anchoring the same to a concrete foundation, cushioning 90 members disposed above and below the base plate, and means secured to the foundation and extending through the cushioning members and base plate for attaching a rail thereto.

4. Means for mounting rails on concrete 95 foundations comprising a base plate, a flange formed on the base plate for anchoring the same to the concrete foundation, a cushioning member between the base plate and foundation, a cushioning member carried between a rail and the base plate, and means 100 formed on the base plate for guarding and preventing lateral movement of a rail with respect to the base plate.

In testimony whereof I hereunto affix my signature in the presence of two witnesses.

JOHN B. LOTT.
